UNITED STATES PATENT OFFICE.

EDWARD L. MEGILL, OF NEW YORK, N. Y.

FEED-GAGE FOR PRINTING-PRESSES.

SPECIFICATION forming part of Letters Patent No. 793,456, dated June 27, 1905.

Application filed July 13, 1904. Serial No. 216,369.

To all whom it may concern:

Be it known that I, EDWARD L. MEGILL, a citizen of the United States, residing in the borough of Brooklyn, county of Kings, and city and State of New York, have invented certain new and useful Improvements in Feed-Gages for Printing-Presses, of which the following is a specification.

This invention relates to the class of feed-guides and gage devices for the proper placing of a sheet on the platen of the press to receive an impression, and particularly to that class of such gage devices wherein the gripper of the press acts to move the sliding gage of the device up to the gage-line on the platen.

The invention embodies improvements in the gage device illustrated and described in my United States Patent No. 712,198, dated October 28, 1902. In a gage device of this class there is a base-plate secured on the platen, a sliding gage mounted in guides, a spring for retracting said sliding gage, and means adapted to be impinged upon by the gripper of the press when the platen moves up to the form for moving the sliding gage up to the gage-line. In the present gage device the base-plate has spurs to engage slits in the tympan-sheet and is capable of adjustment over said sheet, a clamping-plate secured to the base-plate by screws for clamping the device to the tympan-sheet when set, a sliding gage mounted in guides on the base, a hinged toggle device with a coil - spring at its knuckle for moving the sliding gage to and fro, and means engaged by the gripper for depressing the toggle and shifting the sliding gage.

In the accompanying drawings, which illustrate an embodiment of the invention, Figure 1 is a plan view of the gage device as it appears when flattened by the gripper, the position of the latter being indicated in dotted lines. Fig. 2 is a similar view to Fig. 1, but with the upper gage-operating parts omitted. Fig. 3 is a cross-section at x^3 in Fig. 1, but showing the gage retracted. Fig. 4 is a front sectional view of the device, the plane of the section being substantially at line x^4 in Fig. 3. Fig. 5 is a plan view of the base-plate detached from the remainder of the device and shown as mounted in slits in the tympan-sheet. Fig. 6

is a view on a small scale, showing one of the gage devices mounted on the platen of a press. Fig. 7 is an under side view of the gage device detached. Fig. 8 is a plan view of the clamping-plate of the base detached. Fig. 9 is a perspective view of the gage device. Fig. 10 is an illustrative sectional view showing how the tympan-sheet is clamped between the members of the base. Fig. 11 is a fragmentary view showing a compressible form of the gage-head. Fig. 12 is a fragmentary sectional view showing a clamping nut and screw.

In Fig. 6, W designates the platen of a printing-press, X one of the grippers thereof, and Y the tympan-sheet stretched over the platen in the usual way and by the usual means. All of these parts are common in platen printing-presses. On the platen is shown a sheet S in position to receive the impression, the positioning of the sheet on the platen being effected by bottom guides or gages w of any kind and a side guide, as A in this figure, which is a gage device constructed according to the present invention. This gage device will now be specifically described with reference to the figures of the drawings, which are on a larger scale.

B designates a base-plate, which may be of thin metal of a somewhat U shape—that is to say, the base portion has preferably two branches b and b', which project at right angles therefrom, as seen in Fig. 5. On the inner edge of the branch b are two spurs b² and b³, and on the outer edge of the branch b' are two spurs b⁴ and b⁵. All of these spurs project in the same direction and are designed to pass through slits y, Fig. 5, in the tympan-sheet Y and take under the latter. Preferably the prong b² will be the longest, the prong b³ the shortest, and the spurs b⁴ and b⁵ of intermediate length. In the base-plate are set two upright screws b⁶.

C is a clamping-plate, (seen detached in Fig. 8.) This plate has in it two holes c, which register with the screws b⁶, and when the base-plate is placed in position on the tympan-sheet and adjusted, as in Fig. 5, and the clamping-plate is placed in position, with the screws protruding up through the holes, nuts b⁷ are screwed down on the screws and serve to clamp

the tympan-sheet between the plate C and those spurs of the base-plate (b^2 and b^4) which are under the clamping-plate. This serves to hold the gage device to the tympan-sheet 5 firmly in the place set by adjustment along the slits y . It may be stated here that in placing the base-plate it will be convenient to introduce the longest spur first, then the spurs of intermediate length, and, lastly, the shortest one.

On the clamping-plate C are keeper-guides c' to receive the stem of the sliding gage D and hinging-lugs c^2 , in which is hinged the rear plate E of the toggle on a hinge-rod c^3 . 15 This plate E is provided with an arm e , projecting upward normally at an angle into the path of one of the grippers X, and is hinged at its front edge on a rod e' to the front toggle-plate E'. This latter plate has at its front 20 edge a spur e^2 , which engages a stirrup d , struck up from the sliding gage D. At the hinge where the two toggle-plates are connected there is a coil-spring e^3 , which tends to return the toggle to the elevated position seen 25 in Figs. 3 and 9 after it has been flattened, as in Fig. 1, and the pressure is removed. Thus the depressing of the toggle moves out the sliding gage, and when the pressure is removed the spring e^3 retracts the gage to a limiting-stop. As herein shown, this stop is a heel 30 e^4 on the plate E back of the hinge, which comes to a bearing on the outer or rear edge of the plate C. This latter may be slightly turned up, as seen in Fig. 12.

35 The sliding gage D has a gage-head d' of any kind, and the T portion d^2 thereof has at one end d^3 a sliding bearing on the branch b of the base-plate, and at the other end a tongue d^4 , which takes under an elevated keeper b^8 40 on the branch b' of said plate. This latter prevents the gage from lifting up, but permits it to slide freely to and fro to the proper extent.

On the back of the toggle-plate E, in suitable keepers f , may be mounted a bar F, similar to that described in my said Patent No. 712,198, and provided with an arm F', which projects into the path of the gripper to perform the function fully explained in said patent. This bar forms no essential part of the present invention.

Where a gage-head, as d' , is employed obviously the gripper must be set so as not to impinge upon it; but a thin spring gage-head, 55 like that shown in my previous patent, which curves upward by its own resiliency, may be employed, and such a head is shown at d^5 , in Fig. 11. A head of this kind may come under the gripper and will be flattened down 60 thereby.

The operation and function of the sliding gage will be the same as fully set forth in my former patent and need not be explained here.

It will be noted that the peculiar U-shaped 65 form of the base-plate B has the following

important advantages—namely, the branches b and b' extend out and provide a support near the gage-line, giving a broad base for the gage. They extend beyond the normal position of the gage-head, and the spurs b^3 and b^5 70 by extending under the tympan-sheet prevent the sheet being placed from getting under the head of the gage. The beveling back of the ends of the branches b and b' , as seen in Figs. 1, 3, and 5, also assists in preventing 75 the sheet from getting under the base-plate. The four spurs hold the carriers of the plate down firmly. This invention is not, however, limited to the branches b and b' on the base-plate, as good results may be had without 80 them; but the form of base shown is preferred.

Having thus described my invention, I claim—

1. A registering-gage, having a base-plate provided with flat spurs at its respective ends 85 and projecting laterally in the same direction, two upright screws on said plate, one at each end near the said spurs, a clamping-plate with holes to receive said screws, and nuts on the said screws, the said spurs being adapted to 90 engage the tympan under the clamping-plate.

2. An automatic registering-gage, having a base and means for securing it to the platen, a sliding gage, a toggle device for moving said gage up to the gage-line, said toggle device comprising two plates hinged respectively to the base and the gage, and hinged together at the knuckle, and a spiral torsion-spring at the knuckle for retracting the gage. 95

3. An automatic registering gage device, 100 having a base-plate, with branches provided with spurs b^2 , b^3 , b^4 and b^5 at their respective edges, and with screws b^6 and nuts b^7 , a clamping-plate C, with holes to engage said screws, keeper-guides c' , for the gage, and hinging-lugs c^2 , the gage D, slideable in the guides c' and having a stirrup d , a gage-head, and tongues d^3 and d^4 , the former slideable on the base-plate and the latter slideable in a keeper b^8 thereon, and the toggle device for operating 105 the sliding gage, said device comprising the plates E and E', hinged together at the knuckle and provided thereat with a coil-spring e^3 , the plate E being hinged to the lugs e^2 and provided with an arm to be depressed by a gripper on the press, and the plate E', having a hinging-prong engaging the stirrup d on the sliding gage. 115

4. An automatic registering gage device, 120 having a base-plate with lateral spurs adjustable in slits in the tympan-sheet, means for clamping said plate to the tympan-sheet, a sliding gage having a laterally-projecting tongue at its head, and means for moving said gage when the impression is made, the base-plate 125 being provided with an elevated keeper elongated in a direction parallel to the path of the gage-head and under which said tongue plays when the gage moves.

5. A gage device, having a base-plate, means 130

for securing said plate to the tympan-sheet, and a movable gage, said base-plate being provided with branches which extend forward over the tympan-sheet and are provided at their respective outer ends with laterally-projecting parts to engage slits in the tympan-sheet.

6. An automatic registering gage device, having a base portion and means for securing same to the platen, a sliding gage, and a toggle device for moving the gage up to the gage-line, said toggle device being composed of two parts hinged together at the knuckle and one part hinged to the base and the other to said gage, the three hinge-axes being parallel, and a spring connected with the toggle for contracting the same.

7. A registering gage device, having a base, means for securing same to the platen, a sliding gage on the base, and a toggle for operating the gage, said toggle having its three hinge-axes parallel and having its two parts connected by a spring for contracting the toggle.

8. A registering gage device, having a base,

means for securing same to the platen, a sliding gage on the base, and a toggle for operating the gage, said toggle having its three hinge-axes parallel, and a torsion-spring which retracts the gage.

30

9. A registering gage device, having an attaching-base, and a sliding gage thereon provided with a laterally-projecting tongue near its head, the base-plate having an arm which projects out over the tympan-sheet and is provided with an elongated elevated keeper which takes over said tongue and prevents the gage-head from rising.

35

10. A gage device, having a base-plate provided with laterally-projecting flat spurs at its respective sides, said spurs projecting in the same direction and at an angle to the face of the gage, and being of different lengths.

40

In witness whereof I have hereunto signed my name, this 8th day of July, 1904, in the presence of two subscribing witnesses.

45

EDWARD L. MEGILL.
